[57] CLAIM

The ornamental design for a water bottle crate, as shown and described.

DESCRIPTION

FIG. 1 is a top plan view of a water bottle crate showing my new design;

FIG. 2 is a side elevation view thereof, the other three sides being the same in appearance;

FIG. 3 is a bottom plan view thereof;

FIG. 4 is a cross sectional view taken along line 4—4 of FIG. 1;

FIG. 5 is a cross sectional view taken along line 5—5 of FIG. 1;

FIG. 6 is a cross sectional view taken along line 6—6 of FIG. 2;

FIG. 7 is a cross sectional view taken along line 7—7 of FIG. 2;

FIG. 8 is a cross sectional view taken along line 8—8 of FIG. 2;

FIG. 9 is a cross sectional view taken along line 9—9 of FIG. 2; and

FIG. 10 is a cross sectional view taken along line 10—10 of FIG. 1.
